[57] **CLAIM**

The ornamental design for a camera with framing and spacing device, as shown and described.

DESCRIPTION

FIG. 1 is a left front perspective view of a camera with framing and spacing device showing my new design. The broken-line showing of a camera is environmental only and forms no part of the claimed design;

FIG. 2 is a front elevational view thereof;

FIG. 3 is a left side elevational view thereof, the right

side being a mirror image thereto;

FIG. 4 is a top plan view thereof;

FIG. 5 is a bottom plan view thereof.

FIG. 1.

FIG. 2.

FIG. 3.

FIG. 4.

FIG. 5.
